FREEZER PACKAGE RACK AND IMPROVED ARRANGEMENTS THEREOF

Edmund J. Buzicky, St. Paul, Minn., assignor, by mesne assignments, to Whirlpool Corporation, a corporation of Delaware

Application August 22, 1955, Serial No. 529,631

5 Claims. (Cl. 312—304)

This invention relates to an improved multiple positioning and sliding basket arrangement and freezer package rack in and for freezer storage cabinets. More particularly the improvement concerns an open sided basket rack or shelving provided in the preferred form with a tilted bottom portion and slidably mounted within a freezer cabinet for slidably resting another basket thereon in side by side relationship.

Spacers, dividers, and shelf arrangements are conventional for various enclosures. However, in freezer cabinets it is usually the practice to move and shift various objects about in order to get at the desired objects or materials. In such shifting, the unwanted objects are generally stacked to one side or from shelf to shelf each time an object at the back or the bottom of the box is desired. There is therefore required a more convenient space saving shelving arrangement and structure which permits ready access to various portions of the box and to the shelving.

Accordingly it is an object of this improvement in freezer cabinet shelving to provide an economical and convenient labor, time and space saving removable and sliding shelf arrangement which is movable back and forth in the cabinet aperture.

Another object of this improvement in freezer cabinet shelving is to provide a movable rack giving access from the top and side thereof for ingress and egress of the contents contained therein.

An additional object of this improvement in refrigerator shelving is to provide a removable basket shelving with a labor, time and space saving arrangement for additional removable and sliding basket shelving.

A further object is to provide a sliding and removable freezer chest basket open at the top and sides and having a bottom sloping rearwardly on a plane tangential to the normal horizontal and vertical planes of the freezer chest lining.

Additional objects and advantages will be apparent from the following description of the accompanying drawings.

Fig. 1 is a top plan view of an open freezer chest with the door removed showing the improved basket arrangement.

Fig. 2 is a side view of my improved basket shelf structure.

Fig. 3 is a cross section view through line 3—3 of Fig. 2.

Inasmuch as the construction of freezer chests or cabinets are well known the details thereof are not shown or described other than the border molding 10 which conventionally surrounds the opening aperture to the freezer chest and a conventional divider wall or wall spacer 11 spacing off one end of the chest structure. Otherwise the numeral 11 may represent a rod insert adjacent the cabinet aperture between the relative opposite freezer chest side walls (not shown) which serves to support the basket shelving, in the manner as hereinafter described.

The preferred embodiment of the basket shelving is

2

somewhat less in width than half the width of the freezer aperture and is mounted to depend into the freezer cabinet and slide transversely of the longitudinal length of the horizontal cabinet aperture. In this embodiment the basket shelving is a wire frame structure A formed with offset bottom frame side wires or slender steel bars 14 and 15 and parallel aligned top frame side wires or slender steel bars 16 and 17 with end frame member supports.

The end frame supports for the basket frame sides 14 and 16 are integral upright legs 18 and 19 and for the frame sides 15 and 17 the relatively longer integral upright legs 20 and 21. The legs 18 and 20 at their top ends are bent back and down to provide a pair of parallel aligned hooks 23 and 24, respectively. The hooks 23 and 24 are adapted to engage the top edge of support 11 and slide back and forth thereover. The legs 19 and 21 at the opposite end of the basket shelving have their ends 25 and 26 bent back at substantially a right angle and are angularly inclined towards each other and joined by a cross wire or similar slender steel rod 27. The bent portions 25 and 26 and connecting portion 27 are preferably flattened on their top and bottom sides to form a horizontally extending flange adapted to rest upon and slidably engage the edge of the cabinet aperture, or molding 10, and be moved back and forth thereover. In forming the frame side structure it will be apparent from the above description that a straight slender steel rod forms, by proper bending, the continuous siding including the hook 23, leg 18, side 14, leg 19, end 25 connecting piece 27 and end 26, leg 21, side 15, and leg 20 through hook 24.

A center reinforcing wire or slender steel rod 29 is spot welded between the upper frame side 16 and lower frame side 14. The upper frame side 16 is spot welded between the upright leg ends 18 and 19, and the upper frame side 17 is spot welded between the upright leg ends 20 and 21.

The balance of the basket shelving is provided with a back closure wall and a bottom by spot welding a plurality of light, right angularly bent, wires 30 to the frame sides 14, 15 and 17. As more clearly illustrated in Figure 3 taken in conjunction with Figure 2, the base 31 of angular wire 30 is secured at its front end by spot welding to the frame side 14, spot welding its angular bend of slightly less than 90° to the frame side 15 and and spot welding its opposite upstanding end 32 to the top frame side 17. The difference between the length of frame legs 18 and 19 and frame legs 20 and 21 is preferably slightly greater or substantially double the diameter of the frame side portions 14 and 15. This shorter length of the relative front legs 18 and 19 raises the front ends of bottom shelf wires 31, attached to basket shelf rim 14, and the longer length of the relative back legs 20 and 21 lower the back side of the shelf wires 31 to give the shelf or basket bottom a slight incline or backward tilt. While any number of right angular wires 30 may be used to aid in holding frozen commodities and reinforce and strengthen the shelving structure, these wires are preferably widely spaced with a number of intermediate bottom frame wires 34 spot welded in a rearwardly sloping relation between frame sides 14 and 15. The wires 34 serve to fill the spacing between wires 31. A centered cross wire 35 is spot welded to the shelf wires 31 and 34 as reinforcement therefor and to aid in closing the shelf bottom. With the bottom section having a slight rearward incline, goods positioned thereon either from the top of the basket frame or from the open side, between top rim 16 and bottom rim, 14, do not tilt, tip or slide therefrom upon sliding the depending shelving back and forth upon its end supports, as described.

When the basket shelf A is seated upon the support 11

and end molding 10, as shown in Figure 1, a second wire basket B which is of conventional character, illustrated only by the modified conventional upper rim 36 is also mounted in the freezer cabinet aperture to depend in sliding relationship to the basket shelving A and the cabinet molding 11. The ends 37 and 38 of the basket rim 36 are provided with conventional lifting handles 39 and 40, respectively. Each of the sides 41 and 42 of rim 36 have the legs of elongated U-shaped wires or slender steel bars 43 and 44 spot welded thereto. Thus with the basket shelving A pushed back or forwardly (not shown) the bars 43 and 44 slidably support basket B upon either of the basket frame rims and molding 10 permitting movement longitudinally of the cabinet aperture.

It will thus be recognized that by the provision of a basket shelving structure which is relatively more narrow in width and slideable transversely of the freezer cabinet apertures affords a great savings in time and labor with reduction of operating costs. With such basket shelving occupying only a portion of the aperture in the freezing cabinet a further basket element used in conjunction therewith to move or slide longitudinally of the aperture provides for increased time and labor saving in moving or removing top packaged articles or commodities and also improves upon refrigeration efficiency with reduced cost of operation.

In accordance with the patent statutes, I have described the principles of construction and operation of my freezer package rack and improved arrangements thereof, and while I have endeavored to set forth the best embodiment thereof, I desire to have it understood that changes may be made within the scope of the following claims without departing from the spirit of my invention.

I claim:

1. In combination a freezer cabinet having a sliding shelving arrangement therein, said cabinet having a horizontal door aperture, a molding about said aperture and a space divider wall in said freezer cabinet, said sliding shelving comprising a multiple basket arrangement mounted on and supported by said molding about said door aperture and said wall, said freezer cabinet having a longitudinal axis and one of said multiple baskets sliding transversely of said longitudinal axis of said freezer cabinet between said wall and over one edge of said molding, and another basket insert sliding longitudinally of said freezer cabinet axis over another edge of said molding and over an upper longitudinal rim edge of said one basket.

2. In combination, a chest type freezer cabinet, said cabinet being of generally rectangular shape, a first basket slidably supported within said cabinet for movement toward and away from two parallel walls of said cabinet, and a second basket slidably supported for movement toward and away from the other two parallel cabinet walls, said second basket having one edge slidably supported on one of the two first named parallel walls and having an opposite edge slidably supported upon said first basket.

3. In combination, a generally rectangular chest type freezer cabinet having parallel front and rear walls and parallel end walls, a first shelf member slidably supported within said cabinet for movement forwardly and rearwardly between said front and rear walls, and a second shelf member slidably supported for endwise movement between said end walls, said second shelf member being generally rectangular in plan and having one edge slidably supported on one of said first named parallel walls and having an opposite edge slidably supported on said first shelf member.

4. In combination, a generally rectangular chest type freezer cabinet having parallel front and rear walls and parallel end walls, a partition wall connecting said front and rear walls parallel to said end walls, a first basket of generally rectangular form having one side slidably supported on one of said end walls and having a parallel side slidably supported upon said partition wall, whereby said first basket may be moved forwardly and rearwardly, a second basket of generally rectangular shape having one side slidably supported upon said first basket and having a parallel side slidably supported upon one of said first named parallel cabinet walls, whereby said second basket is movable toward and away from said one end wall and said partition wall.

5. The structure of claim 4 and in which the first basket includes a bottom which is inclined downwardly and rearwardly toward the rear wall of the cabinet.
